3 Claims. (Cl. 235—31)

1

There is a great demand prevailing for a portable apparatus appropriate to the sale of tickets, in the first place bus tickets. A great deal is required and should be required of such an apparatus. The apparatus as per the invention in question must be considered as fulfilling every demand. Thus it is of small dimension, light weight, and is easy to carry and handle by a bus, tram or railway conductor. Notwithstanding, it is possible to obtain, by means of this device, 10 tickets plainly printed and to introduce into counting works and register, desired amounts. The changing of figure type wheels, in order to obtain the printing of different ticket prices, is made by easily moved regulating organs. To print and register set amounts one has to operate upon one single driving organ only.

The apparatus as per the invention is principally characterized by the fact that it consists of a case, provided with a mechanism for fastening the apparatus to a waist-strap or the like, on the upper and/or front side of which case there are regulating organs worked upon from the outside, and by aid of which figure type wheels placed in the case can be switched and that a driving mechanism, placed outside the case, is arranged in such a way as to introduce into the counting works a set amount and provide a ticket strip with corresponding printing, the case being furnished with a chute, from which the printed ticket is removed. The regulating organs consist of circle segments, shiftable along a circle arc or rotating around a centre, said segments being provided, around their periphery, with depressions formed as thumb holds, in which are figures or other marks; further there is on the case a bar, common to all these regulating organs and serving as a stop to the thumb. A set amount is transmitted to the counting works by a step gear.

In addition to the item printing figure type wheels 56 adjustable by the regulating organs, there are further figure type wheels, divided in at least two groups (108, 109, 110 and 111, 112) and attached, close to one another, to a general shaft; these wheels lack manipulative movement-transmitting organs to actuate each wheel individually, and the wheel registering from one to nine (one-number wheel) of the group intended for registering consecutive numbers cooperates internally with a carrier on the shaft; the transfer (ten-number transmission) between the one-number wheel and other wheels in the same group is also worked from within, although by means of Maltese wheels (hereafter called star wheels) in the

2

known way; the type wheels 111, 112, of the second group being worked upon manually from the outside, at which the transfer is worked here also from within, by aid of star wheels. The manually moved type wheels 111, 112, are here in driving connection with number wheels 116, 117, readable from the outside, whereas the transfer between the number wheels in question is made from the interior and by aid of star wheels.

The driving device appropriately includes a turnable handlever in such a driving connection with the machine's movement-transmitting organ that, when it is turned in one direction from a rest or zero position, it causes the counting and printing works as well as existing contrivances, if any, for feeding and cutting off the ticket strip, to function, while the lever, when it turns in other direction from the abovementioned rest or zero position, brings the regulating organs, previously 15 adjusted, back to their respective rest or zero position (correction). In order to facilitate the handling of the apparatus, the lever is subjected to a spring influence and tends to assume its rest or zero position. For the same reason, the registering organs are arranged in such a way that they can stay in their set place during several 20 following turnings of the machine but, at the lever's executing the correction movement, are brought back to rest or zero position.

Further, the printing hammer (or hammers) 25 cooperating with the figure type wheels consists of a leaf spring, arranged so as to occupy automatically a rest or middle position, and a carrier moved by the lever is constructed to influence indirectly the abovementioned spring, and load it so that, when the spring is disengaged from the carrier during the machine's operation, the spring executes a printing stroke, then returns to its rest or middle position. Finally, the cutting off device 30 for the printed ticket consists of a cutting mechanism, revolving around a stationary pin, appropriately semicircular in cross section, which cutting mechanism consists of a sleeve cut obliquely in axial direction, the remaining part being approximately of the same length as the width of the receipt strip and forming an edge at an acute angle to the pin, whereat the ticket strip is inserted between the pin and abovementioned edge 35 and is cut off at the turning of the sleeve relative to the shaft.

Thanks to the possibility of combining the abovementioned apparatus with a waist-strap and the special consideration given to its purpose at the fashioning of the case, the adjusting organs, the driving and movement-transmitting

organs and other details of the contrivance, the apparatus has become very easy to handle, and the component construction details function compulsively, though every means of attaining a solid construction has been applied. When the apparatus as per the invention has been executed in the most appropriate way it is thus possible to regulate by simple movements of the thumb of one hand the adjusting organs for marking ticket price and other control signs, to set with a finger grasp another desired marking, for instance a marking corresponding to a stop or station and, by working upon a single driving organ during a machine operation, acquire the registering of all the different adjustments in counting work and/or a control strip, printing, feeding and cutting off of a ticket.

One example of executing the invention is shown on the attached drawing, whereat Fig. 1 shows the front view of the apparatus, partly in section. Fig. 2 shows the apparatus seen from one side likewise with certain parts in section. Fig. 3 shows a section along the line III—III in Fig. 1. Fig. 4 shows the apparatus, partly in section, seen from the opposite side to Figure 3. Fig. 5 shows, on a larger scale a detail of the apparatus seen from the front, and Fig. 6 a section along the line VI—VI in Fig. 5. Fig. 7 shows, likewise on a larger scale the mechanism for cutting off the tickets, seen from the side, and Fig. 8 a section along the line VIII—VIII in Fig. 7.

Fig. 9 is an isometric schematic view of the interior of the machine with parts omitted in the interest of perspicuity.

The contrivance consists, as mentioned before, of a cover 1 provided with suitable hook-formed organs 305 for attaching the apparatus to a waist-strap 306, a left end wall 2, that can be permanently connected with the central part of the case, and a righthand end wall 3, which is connected with the central part by a hinge 4, and further attached with a safety lock not shown on the drawing.

In the machine there are two end walls 5 and 6, between which certain shafts and mechanisms are situated, the walls being attached to a rear plate 7. Furthermore there is, between the walls, a governing plate 8, the purpose of which is to serve as governing or guiding organ for the regulation mechanisms 9, 10, 11, 12, 13. These devices, used for selecting the figure type wheels and the ticket prices, consist of segments provided with thumb grips 14, which segments might appropriately be made of some synthetic resin and be provided, in the thumb grips, with numbers or other suitable markings. In the present case the organ 9 is used for indicating the character of the ticket, as for instance pertaining to a ticket for a grown person or a child, or for a packet etc. Organ 10 is intended for 1-öre, organ 11 for 10-öre, organ 12 for 1-crown and organ 13 for 10-crowns. Thus one can adjust the apparatus from 1-öre up to and including cr. 99.99, and 10 ticket markings. Each segment is attached at its ends to a segment-shaped plate 15, which has for this purpose two projecting parts 16, 17, stretching into two separate grooves 18 at the ends of the segment. The parts are united by pins 19, 20. The plate 15 is thus situated in the centre of the segment, as appears from Fig. 1. The governing plate 8 is provided with slots 21, through which plate 15 stretches. The arch-shaped edge turned from the segment plate 15 is provided with cogs 22 divided in such a way that on each thumb grip 14 come two cogs.

Each segment has on its inner surface undulatory depressions 23 divided in the same way as the thumb grips. The wave tops are not in touch with the governing plate 8, so that only the end surfaces 24, 25 are sliding against this plate. A spring 26 attached to the inside of plate 8 catches into the depressions 23, in order to keep in this way the respective segments in a regulated position. The spring is only situated on one side of each plate 15 and has therefore a breadth somewhat less than half the width of the segment. On the other side of each plate 15 this is provided with guiding cylinders 28, 29, which are in touch with guiding plate 8 and appropriately placed in front of the sliding surfaces 24, 25 of the segment. In this way the friction has been reduced as much as possible.

The cogs 22 on plate 15 engage into a cog-wheel 30 and, a cog-wheel 32. Here must be mentioned that, in the interest of clarity of illustration and avoidance of duplication, all shafts and cog wheels related to the several denominational orders are not shown on the drawings. Thus on Fig. 1, cog-wheels 30 and 32 and a counting work with gearing for the plate 15 only, which belongs to 10-öre-segment 11, while in Fig. 2 is shown the gearing belonging to the counting work for 1-öre-segment 10. The cog-wheel 30 is attached to a differentially rotatable shaft 33, provided with a screwshaped groove 34. On shaft 33 is placed an axially slidable carriage 35 with two side plates 36, 37, which catch into the groove 34 with a small projection 38. Each plate 36, 37 has a recess 39 which fits about a shaft 40 parallel to shaft 33, and between the plates on this shaft is placed a cog-wheel 42. Cog-wheel 42 is slideable along shaft 40, but is prevented (by a spline and groove-connection 43) from turning around the shaft or, in other words, when the cog-wheel is turned, shaft 40 rotates. The mechanism described up to now works in the following manner: When segment 11 glides downwards, i. e. in the clockwise direction as per Fig. 2, the shaft 33 turns, which causes the carriage 35 to glide to the left as per Fig. 1, and in this gliding movement cog-wheel 42 takes part.

The left hand end of shaft 40 stretches through the end wall 5 and here supports a cog-wheel 45, seen in Fig. 1. In Fig. 2 one part of the end wall 5 has been cut off, thus showing only the corresponding cog-wheel 45' for 1-öre registration. This cog-wheel 45, 45' is by means of an intermediate wheel 46, 46', engaging a cog-wheel 47, 47', attached on shaft 48, supporting a counting work 50, the members of which are seen through a window 51 in the case 1. Thus in the present case, there are four counting works, or cumulative registers, i. e. one for 1-öre, one for 10-öre, one for 1-crown, and one for 10-crowns. There therefore is a register for each denominational order. A register totalizes the entries determined by the setting of its associated one of the settable segments 10-13.

There is then also a cog-wheel 42 for each of the four coin values, and all the four cog-wheels are placed around a step gear 52, which at the same time acts as a lock for the cog-wheels. The step gear is in the known manner provided with cogs 53 of different length with recesses between them, and is intended to make a whole revolution during each operation of the machine. By placing the counting works' cog-wheels 42 around the step gear, all the four counting works

can, if necessary, be actuated at the same time by aid of one and the same step gear.

At each regulating organ 9-13, there is a cog-wheel 32, and these cog-wheels are in known manner in connection each with its type wheel 56, by means of sleeves 55.

On the case 1 is placed a bar 57 just below the lowest (marked "0") recess 14 in the segments 9-13, when the latter are in a zero position. This bar is acting as a stop or gliding surface for the conductor's thumb, so that the gliding downwards of the segment further than intended is hereby prevented. Upon actuation of any one of the hand set dials 10-13, a corresponding pinion 30 causes displacement of carriage 35 longitudinally of step gear 52. Simultaneously, pinion 30 rotates a corresponding one of the gears 32 to set the item printing type wheels 56. Following this, lever 60 is actuated clockwise, Fig. 3, from its normal or starting position, forcing the segment 63 to rotate the pinion 64. Pinion 64 is connected to the shaft gear 92 by a one-way clutch drive comprising two fingers 65, 66 carried by the pinion 64 and which may abut a pair of corresponding shoulders 67-68 on the gear 92, when turned in one direction. Thus gear 92 is actuated and rotates the shaft 72 to which it is fixed. Pinion 70 on shaft 72 rotates the gear 73 on step gear shaft 85 thereby rotating the step gear 52 one full revolution. Step gear 52 drives the previously positioned gear 42 and actuates the register 50. The return of the lever 60 to normal position causes pinion 64 to be reset, the gear 92 and shaft 72 and their related elements including step gear 52 remaining idle during the return stroke of the lever.

The rotation of the step gear a whole revolution for each machine operation is effected by the following mechanism:

An actuating mechanism consisting of a manually operable lever 60 (on the left in Fig. 1) is, rotatably mounted on the shaft 81, Fig. 3, running through the step gear 52. The lever 60 is rockable clockwise (Fig. 3) from a normal or starting position for registering and is rockable counterclockwise from the same position for clearing or zeroizing the settable segments 9-13 and the type wheels 56. By aid of pin carriers the lever is connected with two cog segments 62, 63, Figs. 1 and 3, which are likewise rockable around shaft 81, but always follow the turning movements of the lever. The cogs of segment 63 turned towards the interior of the machine engage a cog pinion 64, which supports two catches 65, 66, cooperating with the bar surfaces 67, 68 in an inside notch 69 in a cog-wheel 92 (Fig. 3). This cog-wheel and a second cog-wheel 70 are attached to the shaft 72 supporting cog-wheels 32 and type wheels 56, and cog-wheel 70 is engaging a cog pinion 73, connected with the step gear. The gearing between segment 63 and the cog pinion 64, and between cog-wheel 70 and cog pinion 73 is 2:1, 2:1, respectively, so that, at an approximate turning 90° of the lever 60, cog pinion 64 executes 1/2 revolution and the step gear a whole revolution. The shaft 72 likewise executes 1/2 revolution. When the lever is turned back or counterclockwise, Fig. 3, to the starting point, the step gear 52, cog-wheel 70 and thus also shaft 72 are kept in place, while the catches 65, 66 with the cog pinion 64 are turned back half a revolution, so that these can cooperate with bar surfaces 68 and 67 situated previously opposite the catches.

During the rotation of the step gear 52, the axially positioned cog-wheels 42 are engaged by the cogs 53 of step gear 52, and are thus turned according to the amounts set by aid of segments 10-13, which amounts are registered in the counting works 50. The counting works are cumulative registers.

Segment 63 has a locking surface, cooperating with cog pinion 64 so that, when segment 63 is turned counter-clockwise (Fig. 3), the cog pinion is not actuated. Consequently, the step gear 52, which has been rotated one full revolution, and the registers 50 and type wheels 56 are not disturbed when the lever 60 is returned to normal or starting position. Repeat entries may be made by successive strokes of the lever 60 clockwise from its normal or starting position. On the other hand segment 62 (Fig. 1) is constructed so as to turn a cog pinion 80 only when 15 the lever is turned from the starting position counterclockwise (Fig. 3), whereas cog pinion 80 is not turned when the lever works clockwise. Only when the lever 60 is moved counterclockwise (Fig. 3) from its normal or starting position 20 does it cause segment 62 to rotate pinion 80 on reset shaft 81. Pinion 80 is attached to a so-called correction or reset shaft 81. By aid of this shaft all the segments 9-13 are restored to the starting position by the turning of the lever 25 60, from its normal starting point counter-clockwise (Fig. 3).

As is seen from Fig. 2, each cog-wheel 32, which is turned by cog segment 15, engages a cog-wheel or cog segment 84, revolving on the step gear shaft 85 (Fig. 1). Each such cog-wheel 84 has a side projection 86, and on the shaft 85 is a pin 87, intended to cooperate with projection 86. On the correction shaft 81 is a cog segment 88, which via an intermediary wheel 89 engages a cog-wheel 90, attached to the step gear shaft 85. The way of working of this mechanism is as follows: When segments 9-13 are set, the cog segments 84 are turning counter-clockwise (Fig. 2). When the lever 60 is turned counter-clockwise 45 from its normal position (Fig. 3), correction shaft 81 is turning clockwise, and the step gear shaft is turned by aid of the intermediary wheels 89, 89', also clockwise, so that pins 87 carry the angle-displaced cog-segments 84 and related cog-wheels 32 to the starting position. Thus segments 9-13, cog-wheels 32 and type wheels 56 are all simultaneously turned back to their starting positions.

Cog-wheel 92 on shaft 72 engages a cog pinion 55 93, attached to a shaft 94. The cog-wheel device is such that shaft 94 is turning (clockwise) (Fig. 2) only when lever 60 is turned clockwise. This is because cog wheel 92 and shaft 72 are driven from a one way clutch between cog pinion 64 and cog wheel 92. Shaft 94 supports, at the end farthest from cog-wheel 93, a ticket feeding roller 211, the right hand part 95 of the machine being intended for ticket printing-, feeding and cutting mechanisms. Closely connected with segments 62, 63 are further a stop segment 97 (Fig. 3) and a plate 98 with a curve groove, consisting of two parts. Stop segment 97 has the object of preventing the returning of lever 60 to its starting point, before the lever has completed 70 its turning movement. The curve groove of plate 63 has a zero position and two parts 99, 100. The groove accommodates a pin 301, attached to a revolving two-armed lever 302, 303, and influenced by a spring 304. This spring has as its 75 purpose to restore the lever to the starting posi-

tion, as soon as it is released. If one turns the lever clockwise, pin 301 is forced to follow the groove 100 from approximately the periphery to the centre of the plate 98, and when the lever is released, spring 304 pulls arm 302 with pin 301 to the left (Fig. 3), so that plate 98 and therefore with the lever is turned to its starting point. The same is the case, if the lever is turned counter-clockwise, in which circumstance pin 301 moves in groove 99, causing spring 304 to tighten. When the lever is released, spring 304 pulls arm 302 again to the left, whereat the lever is turned clockwise to the starting position.

Inside case 1 is a stationary plate 101 with an opening 102, and to said plate is attached a hollow cylinder 104 provided with a bottom 103 (Figs. 5 and 6). Through the opening 102 and a corresponding opening in the cylinder bottom stretches the shaft 105, supporting sleeves 55. To the bottom is attached a spindle 106 (Fig. 6), which supports transfer pinions, serving as carrying over transmission elements. To the outer circumference of cylinder 104 are attached three type wheels 108, 109, 110 for indicating consecutive number, and besides these two other type wheels 111, 112 for indicating other markings, such as the price of a ticket, the latter type wheel 112 is partly attached also around a supporting plate 113, resting on shaft 105. This plate is freely mounted on cylinder 104 in such a way that it does not take part in the rotating movements of shaft 105. To supporting plate 113 there is attached a cylindrical core 114, around which a hand operable wheel 115 is rotatably mounted. Further are, on this core attached two counting wheels 116, 117, which by means of a carrying over transmission organ 118 are connected with each other. Counting wheels 116 and 117 may be used to indicate the price of a ticket. On the outer end surface of kernel 114 is screwed on a hood 119 with a window 120, through which the indication of counting wheels can be read.

Hand wheel 115 is at its end surfaces provided with pins 121, 122, which pins catch into an inner toothed in type wheel 112 and counting wheel 116, respectively. A stop mechanism consisting of a ball 123 worked upon by a spring, operating with stop gaps in hand wheel 115, keeps type wheels 112, 111 and counting wheels 116, 117 in their set position.

Type wheels 108, 109 and 110 are counters for totaling the number of consecutive operations of the machine.

Inside figure-type wheel 110 is a device which feeds this unity wheel 110 stepwise. It consists of a plate 126, attached to shaft 105 f. i. by pin 125, which plate has two cog gaps 127, 128. Cooperating with this plate and the cog gaps respectively is a star wheel 129 on spindle 106, and this wheel again is arranged so as to cooperate with and advance unity wheel 110 step-by-step, which has, for this purpose, inner cogs 130. On the device shown, the shaft 105 is made to execute $\frac{1}{2}$ revolution at each machine operation. It is, however, evident that the shaft can also execute a $\frac{1}{3}$ revolution or a whole revolution, in which case plate 126 must be provided with three cog gaps or only one cog gap, respectively.

As is seen by Fig. 5, the feeding device inside the unity wheel 110 renders possible the placing of type wheels 111, 112 close to the type wheel 110 of the very numbering work, so that the total printing organ 108, 109, 110, and type wheels 111, 112 needs much less space than otherwise, as the feeding mechanism for the unity wheel is placed

outside this wheel. The printing and cutting mechanism of the apparatus is shown in Figs. 4, 7 and 8. Besides the number type wheels 56, 108-112, there are printing types 202, 203, 204 which from a store cylinder (not shown in the drawing) via guide cylinders 206, 207 is carried past the printing types, a governing cylinder 208, and out through an opening 209 in the case 1, Fig. 4. Just opposite guiding roller 208 is the feeding wheel 211, which has appropriately the form of a knurled roller attached to a shaft 212, which makes a whole revolution, when the strip is to be printed, fed and cut off. The cutting mechanism is placed between guiding roller 208 and the opening 209 and consists of a stationary pin 307 and a sleeve 308 revolving around same. The pin has been given up to a length corresponding to the width of the receipt strip—the form of a semicircular cross section, and the sleeve has up to a corresponding part been cut off along a line, which forms an acute angle to the sleeve shaft, so that an oblique edge 309 has been attained (Figs. 7 and 8). When sleeve 308, at the end of the operation of the machine, via a cog-wheel pinion 310, 311, is turned around, the printed part of the ticket strip, fed forth between pin 307 and edge 309, will be cut off. The shaft 212 with wheel 211 is attached to a bracket 213, resting on the frame of the apparatus. The bracket has a notch in order to make place for the wheel and it is furthermore cut off opposite guiding roller 208, so that the wheel at this point protrudes from the bracket. The circumference of the wheel is broken, one segment having been cut off, i. e. on that part of the wheel which is normally opposite guiding roller 208. The remaining part of the circumference is knurled in order that the paper strip may be fed forth only when the wheel with its knurled part cooperates with the guiding roller, during the rotation.

On the bracket 213 surface, opposite the guiding roller 208 is, by means of screws, attached a leaf spring 214, constituting the very printing hammer as per the invention. The leaf spring has a notch in order to make place for wheel 211 and a pin 216 attached to one of the side flanges of the wheel. From the fixing place the leaf spring extends from the bracket somewhat past the outer printing type, in the direction of the case 1 wall opposite opening 209. This arrangement permits the free operation of the leaf spring towards the printing types around an imagined line at right angles to the longitudinal direction of the spring, this line being in the neighbourhood of fastening screws 215, while the swinging movement in the opposite direction is blocked in such a way that the part of the leaf spring which is connected with the fastening place, gets in contact with bracket 213. On the leaf spring are set pads 217, 218, 219, preferably of rubber, by aid of which the paper strip is pressed against the printing types.

The leaf spring is actuated by the following mechanism. Bracket 213 supports, parallel to shaft 212, a spindle 220, on which is revolving a lever with a short arm 221, directed towards shaft 212, and a longer arm 222, stretching towards the loose end of the leaf spring. The loose end of the latter arm is movably connected with the loose end of the leaf spring by aid of a loop, placed on the latter.

The mechanism works in the following way:

The different parts occupy the starting positions shown on the drawing. Shaft 212 is turned one revolution at a time. When the shaft has

turned about 150°, pin 216 will come in contact with the short lever 221; during the continued turning of the shaft, corresponding to an angle of about 60°, lever 221 is carried forth, so that the longer lever 222 turns clockwise, carrying with it flat spring 214, which is bent around point 224 and is set. Now, as shaft 212 continues to turn, pin 216 relinquishes the free end of lever 221, spring 214 will snap back to its original position, previous to which, however, it has swung past this position and around a rotation shaft, placed nearer to attaching screws 215 than the point 224, and, by aid of the pads, presses the paper strip against the types. When spring 214, from a printing position, swings back to its starting point, it may, it is true, execute small oscillations, but these are so slight that the spring does not come in contact with the paper strip. During a continued angle movement of about 90°, the strip is fed forth and then cut off, and during the remaining rotating movement shaft 212 turns with wheel 211 and pin 216 to the starting position shown on the drawing.

In the mechanism shown, it has been presumed that the receipt or the ticket is cut off at a point lying, at the starting position of the two parts, between printing types 56, 108-112 and printing block 202. Printing block 202 and type wheels 203 for instance indicate date, firm name, and other date which are constant during the use of the machine. Before the bringing forward of the ticket, an impression of printing types 202 and 203 has already been made between opening 209 and type wheels 56, 108-112, and, preceding the feeding forth, the amount, consecutive number, and other marking by type wheels 56, 108-112, have been added; at the same time the still uncut ticket next following is furnished with printing from types 202 and 203.

The mechanism and the details may vary. Thus two pins could be used instead of pin 216, or else a curve formed organ for facilitating the turning of lever 221, 222 and the tension of spring 14.

Several modifications are of course imaginable inside the field of this invention, several details of the apparatus being executed in another way than shown in the kind of execution above, without it being necessary to give up the idea at the base of the invention.

Having now described my invention, what I claim as new and desire to secure by Letters Patent is:

1. In apparatus of the class described, the combination comprising a plurality of registers operable to accumulate in one of said registers values selected from one denominational order and to accumulate in another of said registers values selected from a different denominational order, a rotatable shaft and means actuated thereby for actuating one of said registers, there being one of said rotatable shafts and register-actuating means for each of said registers; a hand settable gear segment for each of several denominational orders, said gear segments being pivotally mounted about a common axis; mechanisms for setting-up values determined by the positioning of individual ones of said gear segments, each of said setting-up mechanisms comprising a differentially rotatable shaft, a carriage positionable by said differentially rotatable shaft, a coupling gear splined to one of said first-named rotatable shafts and slidably longitudinally thereof by said carriage, gearing connecting between an individual one of said gear segments and its

associated differentially rotatable shaft for positioning said carriage and coupling gear proportionally to a selected set position of the associated gear segment about its pivot center; a rotatable step gear common to all of said registers, said step gear being mounted on an axis central to all of said coupling gears and engageable therewith, and means for rotating said step gear to drive all of said coupling gears and enter values in the respective registers corresponding to the values determined by set positions of the gear segments of the respective denominational orders during one revolution of said step gear.

2. In apparatus of the class described, the combination comprising a plurality of registers operable to accumulate in one of said registers values selected from one denominational order and to accumulate in another of said registers values selected from a different denominational order, a rotatable shaft and means actuated thereby for actuating one of said registers, there being one of said rotatable shafts and register-actuating means for each of said registers; a hand settable gear segment for each of several denominational orders, said gear segments being pivotally mounted about a common axis; value setting-up mechanism associated with individual ones of said gear segments and individual ones of said rotatable shafts, each of said setting-up mechanisms comprising a differentially rotatable shaft, a carriage positionable by said differentially rotatable shaft, a coupling gear splined to one of said first-named rotatable shafts and slidably longitudinally thereof by said carriage, gearing connecting between an individual one of said gear segments and its associated differentially rotatable shaft for positioning said carriage and coupling gear proportionally to a selected set position of the associated gear segment about its pivot center; a rotatable step gear common to all of said registers, said step gear being mounted on an axis central to all of said coupling gears and engageable therewith; means for rotating said step gear to drive all of said coupling gears and enter the values corresponding to the positions of said coupling gears with respect to said step gear as determined by the set positions of said gear segments, said means including a manipulative handle pivotal in one direction from a predetermined position for rotating said step gear one revolution to actuate said registers, and means actuated by said manipulative handle for restoring said gear segments to zero positions when said handle is pivoted in the opposite direction from said predetermined position for restoring said gear segments to zero positions.

3. In apparatus of the class described, the combination comprising a plurality of registers operable to accumulate in one of said registers values selected from one denominational order and to accumulate in another of said registers values selected from a different denominational order, each register including a plurality of numeral wheels and transfer mechanism, a plurality of settable gear segments pivoted about a common axis, there being one gear segment for each of said registers, means for entering values in said registers corresponding to values determined by selected positions of said gear segments, said entering means comprising a rotatable step gear common to all said registers and gear sectors, a pair of rotatable shafts for each of said gear sectors, one of said rotatable shafts being differentially rotatable by an associated gear segment and having a helical groove thereon, a carriage

mounted on said differentially rotatable shaft and adapted to be guided axially thereof by engagement with said helical groove, a coupling gear splined to the second of said pair of rotatable shafts and adapted to be guided axially thereof by said carriage, all of said rotatable shafts being mounted on axes parallel to the axis of said step gear and distributed around said step gear to locate said coupling gears for actuation by said step gear, means between the second rotatable shaft of each pair of said pairs of rotatable shafts and an associated one of said registers for actuating said register, gearing for transmitting motion of each of said gear segments to its associated differentially rotatable shaft for positioning its associated coupling gear longitudinally of the axis of said step gear in proportion with the set position of the gear segment, and means for rotating said step gear to drive all of said coupling gears for entering in the 20 respective registers the values corresponding to the set positions of the gear segments.

GUNNAR ERIK SUNDMAN.
